(57) **CLAIM**

I claim the ornamental design for shotgun shell bottle, as shown and described.

DESCRIPTION

FIG. 1 is a perspective view of the shotgun shell bottle (the vertical lines being part of the bottle design).

FIG. 2 is a top view of the bottle (the vertical lines being part of the bottle design).

FIG. 3 is a front view of the bottle (the left side, right side and rear views being identical to the front view); and,

FIG. 4 is a front view of the bottle with the cap withdrawn. The text in broken lines forms no part of the design. The shading in the figures does not represent color.
